UNITED STATES PATENT OFFICE

JAMES H. STEELE, OF DENVER COLORADO

ATHLETIC TIMER

Application filed February 28, 1928. Serial No. 257,606.

This invention relates to improvements in timers for athletic events.

In the playing of games such as foot ball and basket ball, the games are divided into 5 periods of a given length. It frequently happens, however, that for various reasons time must be taken out and this requires careful and painstaking effort on the part of the time keeper.

10 It is the object of this invention to produce a timing device comprising a clock gear train having means for selectively moving any one of two pointers over a graduated dial indicating elapsed time in minutes, one of these 15 pointers can be used for indicating the time actually played and the other the time "taken out" so that the sum of the two readings will give the actual length of each period. Means is provided for quickly connecting one pointer to the clock arbor and disconnecting the other pointer and for applying a friction brake to the disconnected pointer so that it will be held against accidental movement while disconnected from 20 the clock arbor.

In order to more clearly describe my invention, reference will be had to the accompanying drawing in which one embodiment thereof has been illustrated, and in which:

30 Fig. 1 is a side elevation of my improved athletic timer, portions being broken away to more clearly disclose the construction;

Fig. 2 is a section taken on line 2—2, Fig. 1;

35 Fig. 3 is a section taken on line 3—3, Fig. 2; and

Fig. 3 is a section taken on line 3—3, Fig. 3.

As the clock gear train employed is old 40 and well known no attempt has been made to illustrate it in detail, and therefore only such parts thereof have been shown as cooperate with my specific improvement. Numeral 1 represents a base on which is supported a casing 2. Located within the casing is a frame comprising members 3 and 4 to which the gear train is secured in the usual manner. A barrel 5 contains a spring and has secured to it a great wheel 6 which 45 meshes with a pinion 7 on arbor 8. The

escapement has not been shown but may be operated through wheel 9. In this particular embodiment arbor 8 will be presumed to rotate once every hour and corresponds to the ordinary minute hand arbor. Secured 55 to the outer end of arbor 8 is a gear wheel 10, and an arm 11 which has one end provided with a hub 12 through which the end of arbor 8 is inserted. This arm is held in place by a pin 13. The free end of arm 11 is provided with a downwardly extending pintle 14 on which is journaled a compound gear wheel consisting of a toothed gear 15 that meshes with gear 10 and a friction gear 16, whose periphery is V-shaped. The outer 60 edge may be formed from a rubber ring 17 if desired. Two arbors 18 and 19 are journaled in suitable bearings in members 3 and 4 and extend through the back 20 of the casing and through the dial 21. The rear end of arbors 18 and 19 are provided with knurled heads 22 and 23 by means of which they may be rotated for the purpose of setting the pointers to zero. Secured to the front ends of arbors 18 and 19 are pointers 24 and 25. 65 Pointer 24 has its arbor concentric with dial 21 and its point travels over the scale 26, which is divided into sixty divisions, each of which represents one minute. Pointer 25 has its arbor 19 eccentric with respect to dial 21 and its point travels over the scale 27 which may be divided into minute spaces. Pointer 25 must, of course, be shorter than pointer 24, but can be made longer than shown. Arbors 18 and 19 are provided 70 respectively with friction gear wheels 28 and 29 whose peripheral surfaces have V-shaped grooves with which the friction tire 17 on gear 16 may cooperate. By moving the arm 11, wheel 16 may be brought into contact 75 with either one of gears 28 and 29. A lever 30 is pivoted at 31 and extends through a slot in the casing terminating in a handle 32. A spring 33 has its ends attached to pin 34 on arm 11 and pin 35 on lever 30, and is 80 under tension. When lever 30 is in the position shown in Fig. 3, spring 33 will pass over the center of arbor 8 and will move arm 11 so as to bring wheel 16 into operative 85 engagement with gear 28 and therefore when 90 95 100

arbor 8 rotates, pointer 24 will also be rotated. A spring 36 has its center portion soldered or otherwise secured to arm 11, and the ends of this spring extend across wheels 28 and 29 and when wheel 10 is moved into contact with gear 28, spring 36 will engage wheel 29 to serve as a friction brake and when gear 16 is moved into operative relation with gear 29, spring 36 will contact with wheel 28.

10 If handle 30 is moved downwardly from the position shown in Fig. 3, the center of spring 33 will pass the center of arbor 8 and as soon as it passes below arbor 8, arm 11 will be moved counter clockwise by a snap motion and gear 16 will come into operative engagement with wheel 29 and at the same time a brake will be applied to wheel 28. It is evident therefore that by simply moving lever 30 up or down, either one of pointers 24 or 25 may be made operative and the other clamped against movement by the brake spring 36.

20 The actual time of playing may be indicated by pointer 24 and "time out" by pointer 25. At the beginning of each period the pointers can be returned to zero position by means of the caps 22 and 23.

It is apparent that the same results may be obtained by specifically different means and therefore the example shown and described should be considered as illustrative only.

Having described the invention what is claimed as new is:

25 1. A device of the class described comprising, in combination, a clock gear train having an arbor that rotates at a uniform speed, two independently movable pointers, an arm rotatably secured to the arbor, a gear wheel carried by the free end of the arm, said gear wheel being operatively connected with a similar gear on the arbor whereby it will be rotated from the arbor, and means for operatively connecting the gear wheel on the end of the arm with either one of the pointers and for simultaneously applying a clamping device to the other pointer.

30 2. A device of the class described comprising, in combination, a clock gear train having an arbor that is rotated at a uniform speed, two pointers mounted for rotation about the axes of spaced pivots, a friction gear wheel secured to each pointer pivot, an arm having one end pivoted to the rotatable arbor and the other end freely movable, a gear rotatably secured to the free end of the arm, a gear carried by the arbor, said gears being operatively connected, a friction gear wheel carried by the free end of the arm, and with the gear on the free end of the arm so as to be rotated thereby, said friction gear wheel on the arm being adapted to separately engage the friction

gear wheels on the pointer pivots, and means for moving said arm about the arbor so as to bring the friction gear wheel carried by it into engagement with either one of the gears carried by the pointer pivots.

3. A device of the class described comprising, in combination, a clock gear train having an arbor that is rotated at a uniform speed, two pointers mounted for rotation about the axes of spaced pivots, a friction gear wheel secured to each pointer pivot, an arm having one end pivoted to the rotatable arbor and the other end freely movable, a gear rotatably secured to the free end of the arm, a gear carried by the arbor, said gears being operatively connected, a friction gear wheel carried by the free end of the arm, and connected with the gear on the free end of the arm so as to be rotated thereby, said friction gear wheel on the arm being adapted to separately engage the friction gear wheels on the pointer pivots, and means for moving said arm about the arbor so as to bring the friction gear wheel carried by it into engagement with either one of the gears carried by the pointers and for applying a friction brake to the pointer not connected with the friction gear.

In testimony whereof I affix my signature.

JAMES H. STEELE.
